UNITED STATES PATENT OFFICE.

HERVÉ SCHWEDERSKY, OF NEW YORK, N. Y., ASSIGNOR TO UNDERWOOD TYPEWRITER COMPANY, OF NEW YORK, N. Y., A CORPORATION OF DELAWARE.

MANIFOLDING APPARATUS FOR TYPEWRITING OR OTHER WRITING MACHINES OR APPLIANCES.

Application filed July 24, 1923. Serial No. 653,408.

My invention relates to improvements in manifolding apparatus wherein writing is to be produced by the use of a typewriter or similar machine or other method and the 5 employment of means whereby the imprint struck or made upon a first sheet of paper shall be transferred also to a number of sheets of paper lying below the first sheet, arranged in such manner that the various 10 sheets of paper upon which writing is to be made shall be capable of movement as successive lines are to be written, while the carbon paper or other medium designed to make duplicate copies upon the sheets of 15 paper lying successively below the first sheet, remain in a substantial fixed position.

My invention employs novel means for the accomplishment of the purposes above indicated and is capable of many modifications in structure and use. Different widths and kinds of work-sheets may be employed and various numbers of carbons and copies may be used and obtained and different mechanical forms of structure may be employed for the purpose of accomplishing the 20 results sought.

For the purposes of my invention, I have constructed a preferred form of device which is described herewith, and is shown 25 in the drawings presented.

In the drawings Figure 1 is a front view of the apparatus which is shown attached to a typewriter of ordinary construction, the sheets of paper and carbon strips are in position ready to operate, the typewriter ribbon has been removed to insure more clearness to the drawing. Figure 2 is a section on the line 2—2 Figure 1 and shows a cross-section of the apparatus. Figure 3 is a section 30 on the line 3—3 Figure 1 and shows means of feeding and maintaining strips of carbon paper in position and in constant and uniform tension. Figure 4 is a detail view from line 4—4 Figure 3 and shows details of apparatus to feed carbon paper and means of raising and lowering strips of carbon paper, being the left hand clamp and take up device. Figure 5 is a sectional view 35 on line 5—5, Figure 4 and shows a section of the take up device. Figure 6 shows the right hand roller clamps which are used to feed the carbon-strips. Figure 7 is a front view of splitters to be used in separating forms attached together on the side and known on the market as fan-fold, tie-fold 55 forms and the like. Figure 8 is a section at 8—8 Figure 7 and shows a section of the splitters.

In employing my invention, the structures described are fastened to a typewriter of 60 any usual construction. Similar numbers indicate similar parts in all of the drawings.

1 is a feed cylinder of a typewriter of any usual construction. 2 is the rear feed roller of such machine. 3 and 4 are auxiliary feed rollers. 5 is a power transmitting roller, transmitting the rotary movement of cylinder 1 to feed roller 4. 6 is a manifold pack of paper or work-sheets in operative 65 position. 7 are the strips of carbon in operative position as drawn from the supply reel or spool 8. 9 is a paper guide of the machine. 10 is a paper guide plate. 11 are supports of rollers 3 and 5. 12 are arms mounted on a shaft 13 and carrying a shaft 70 14 on which rollers 4 are mounted. 15 are springs which maintain feed roller 4 tightly pressed against paper carried between it and feed roller 3. 16 is a ribbon vibrator. 17 is a paper guide plate mounted on 18 which is part of the structure of the typewriter carriage. 19 is an automatic take up device actuated by a coil spring 20 and which maintains the carbon strips 7 in constant and even tension between clamp 21, 85 which holds the carbon fast upon one side of the writing line and clamp 22 which holds it on the other side of the writing line. 23 are plates on which the take up device 19 and clamps 21 and 22 are mounted; plates 23 are maintained in position against the plate 29 by elbow ears or bars 35 which slide in slots 35' in plate 29. Plates 23 are actuated by pinions 25 engaging in racks 24 which are attached to plates 23. 26 are thumb wheels designed to actuate pinions 25. 29 is the plate placed in front of cylinder 1 and which is used as a background or platen to obtain impressions 90 from the types; it also serves as a support for all the above described parts, which are mounted upon it. Plate 29 is fastened by elbows 30 to bar 31 which is a structural part of the typewriter carriage. Plate 29 is also supported by arms 32 which are fixed to carriage 18. 33 is a knife attached to arms 12 and extending between them upon 100 which the sheets of paper may be conven-

iently torn off as they are completed. 36 is a bulge in the plate 29 at the line of writing. 37 are splitters designed to cut edges of fanfold printed forms. They are supported by arms 38. These when needed are attached to paper-table or guide plate 17 by screws 39 and can be adjusted to any width of work-sheets through slots 40 in arms 38. 41 are metal fingers or pins mounted on plate 28 on either side of clamp 21 and which pins guide strips of carbon 7 when clamp 21 is open and fresh carbon is pulled through. 42 is a thumb wheel mounted on clamp 22 and is used to feed or draw fresh portions of carbon to the position of writing.

In the operation of my device, sheets of paper for an original and as many copies as may be desired are inserted in the machine, by sliding the ends of different sheets or strips of manifold paper along guide plate 17 until they engage between cylinder 1 and feed roller 2. Cylinder 1 is then turned in the ordinary manner by a knob 50 to cause the paper to move forward. As the paper moves forward it is guided by guide plate or apron 10 and passes between guide plate 10 and lower end or lip 29^a of plate 29 which comes close enough to cylinder 1 to prevent the paper from sliding between cylinder 1 and plate 29. As the paper continues to move forward it is further guided by paper guide 9 until it passes between feed rollers 3 and 4. The feed roller being actuated through the idler roller 5, by the cylinder 1 and both the rollers 3 and 5 being firmly in contact. By means of the actuation of the roller or cylinder 1 and the feed roller 3 in contact respectively with the rollers 2 and 4, the paper is positively and accurately fed forward without opportunity for slipping or disarrangement.

After the paper has been brought beyond the guide plate 10 and before it is introduced between the rollers 3 and 5, strips of carbon paper or similar material 7 are drawn from the reel or supply magazine 8 behind carbon guides 41 and through the clamp 21 which has been opened to allow the same to be inserted loosely and then drawn through the take up 19 as shown on Figure 3; said clamp being operable by a handle 51 at its upper end, by which it may be swung forwardly about a hinge 52 and against the tension of a spring 53 at its lower end to open said clamp.

The strips of carbon paper or other similar material are then introduced between the several sheets of manifold paper 6 upon which impression is to be secured, one strip 60 of carbon paper being placed in front of each sheet upon which a duplicate copy is to be produced.

Thereupon the strips of carbon paper are drawn through the open clamp 22. This clamp is composed of two small rollers or

cylinders in close contact. One of these cylinders is equipped with a thumb wheel 42 and pivots on a hinge 43; it is maintained in place when closed by spring catch 44. Whereupon the clamp 21 is set and the carbon paper is pulled through by hand through the open clamp 22 until each of the strips is eventy taut. Thereupon clamp 22 is set. Thumb wheel 42 is then turned until the take up device produces the proper tension, 70 by being rotated about its axis, to hold the strips of carbon properly in place. Rollers of clamp 22 are prevented from turning in the direction to loosen their tension by means of a small ratchet. The strips of carbon paper are now in operative position.

When all this has been accomplished the paper 6 upon which the original and the desired copies are to be written is then thrown forward by turning the cylinder 1 in the 85 usual manner and the ends of the paper as the same come forward are inserted between the feed roller 3 and the pressure roller 4.

Thereupon and thereafter as the cylinder 1 is turned in the usual manner, the paper 6 90 upon which writing is desired to be made is moved forward as in any typewriter of the kind indicated, which may be a Remington No. 10 typewriter, while the carbon paper 7 remains in place, the spring tension being 95 such that any slight displacement which may be caused at the middle of the carbon paper 7 by reason of friction of the moving paper 6, will be taken up and re-adjusted.

The take up 19 also serves to overcome any 100 tendency to loosening in the carbon paper 7, by reason of the pounding of the keys upon it in operation, in that manner maintaining the carbon paper 7 always in correct operative position.

When the carbon 7 has become worn, the clamp 21 may be loosened and the clamp 22 may be turned around by means of thumb wheel 42 for the purpose of drawing in fresh sections of the strips of carbon paper from 110 the reel 8 which is supported on the carriage to travel therewith.

As a means whereby it is possible to continue a longer use of any section of the ribbons or strips of carbon paper, I have provided that the supports 23 which carry the clamps 21 and 22 and the take up device 19, may be bodily raised and lowered through the turning of the pinion 25 against the sprocket on the bar 24 by means of thumb screw 26, in that manner bringing into use fresh surfaces as long as any such exist, whereupon the strips of carbon paper may be drawn forward as before indicated and fresh sections put in operative position.

Strips of manifold papers are sometimes made in what are known as fanfold forms or the like, being perforated and folded back and forth to form separate plies, the lines of the perforations enabling the plies to be torn 130

off easily. For the purpose of rendering my device applicable to paper of such type I have provided cutters or splitters 37 to be inserted between the paper and in such manner that the perforations will be cut by the knives 37 as the paper is carried forward in the operation of the machine, the wings or cutters 37 being supported by the bar 38 fixed to the guide plate 17 and so arranged as to be adjusted to any width of paper desired, the adjustment for different widths of work-packs being effected through the slots 40 in the bars 38, and the screw 39 adapted to hold the bars in place upon the frame of the machine.

Upon the plate 29 I have shown a bulge 36, extending lengthwise of the roller 1 and in front of the same, one purpose of the bulge being to form a relatively fixed bar-platen which may accommodate the curved or concaved form of type faces ordinarily employed in typewriters which are provided with cylindrical platens.

When upper types 54 and lower-case types 55 are used, the bulge will be particularly useful, but in the event that my device is employed upon typewriters having but one set of characters, to be used without case shifting, then flat letters would be preferable and the bulge may be eliminated.

It is apparent that many modifications of the device described may be made without departure from the invention as made by me.

The mechanical arrangements or equivalent thereof may be of any convenient form or construction.

The form of typewriter employed may vary according to the work to be done. Any well known form of construction may be employed.

The writing to be duplicated may be produced as indicated by a typewriter or may be produced in any other manner and duplicated by the means set forth. The strips 45 of carbon paper or other material may be made of any desired width and my invention is not limited to their use in single line work, but may be employed with equal facility.

Having now described my invention, what I claim and desire to secure by Letters Patent is:—

1. A manifolding device for a typewriting machine, said device including a plurality of copying strips stretched lengthwise of the platen at the printing line, and between which strips individual plies of work-sheets may be fed, devices for securing the ends of the strips, and resilient means co-operating with all of said strips to hold them under tension in the direction of their length, so that the work-sheets may readily be advanced line by line relatively to said strips; said tensioning means mounted between said end-securing devices, and operable independently of the latter.

2. In a typewriting machine, the combination with a platen against which typed impressions are to be made through an inking medium, of means including a pivoted take-up through which the inking medium is threaded, and a spring which tends to rotate said take-up to maintain the inking medium in a taut condition at the printing line of the platen.

3. In a typewriting machine, the combination with a platen against which typed impressions are to be made on a plurality of superposed work-sheets through a plurality of superposed inking strips, of means at each set of ends of said strips for securing said set, means including a take-up pivoted between said end-securing means, and through which all of the inking strips are threaded, and a spring which tends to rotate said take-up to maintain the inking strips in a taut condition at the printing line of the platen.

4. In a typewriting machine, the combination with a platen against which typed impressions are to be made through an inking medium, of means including a pivoted take-up through which the inking medium is threaded, and a spring which tends to rotate said take-up to maintain the inking medium in a taut condition at the printing line of the platen, said take-up having members around which the inking medium passes on opposite sides of the pivot, for forming a loop in the inking medium.

5. In a front-strike typewriting machine, the combination of a platen, means to support a plurality of carbon-strips in flat condition in front of said platen, means to conduct a plurality of work-sheets in flat condition in front of the platen between the carbon-strips to keep at a minimum any tendency of the work-sheets to drag the carbon-strips with them during line-spacing of the work-sheets, and means to shift said carbon-strips vertically to present fresh portions to the printing line.

6. In a front-strike typewriting machine, the combination of a platen, means to support a plurality of carbon-strips in flat condition in front of said platen, means to conduct a plurality of work-sheets in flat condition in front of the platen between the carbon-strips to keep at a minimum any tendency of the work-sheets to drag the carbon-strips with them during line-spacing of the work-sheets, and means comprising a rack to shift said carbon-strips vertically to present fresh portions to the printing line.

7. In a front-strike typewriting machine, the combination of a platen, means to conduct a plurality of work-sheets in flat condition in front of the platen, means to support a plurality of carbon-strips in flat condition in front of said platen and between said

- work-sheets, clamps to hold the carbon-strips in front of the platen, brackets for said clamps, racks on said brackets, a rotatable shaft, and pinions on said shaft meshing with said racks by which the carbon-strips may be raised and lowered relatively to the printing line of the platen to bring fresh portions into use.
8. In a front-strike typewriting machine, 10 the combination of a platen, means to support a plurality of carbon-strips in flat condition in front of said platen, means to conduct a plurality of work-sheets in flat condition in front of the platen between the carbon-strips to keep at a minimum any tendency of the work-sheets to drag the carbon-strips with them during line-spacing of the work-sheets, and means to draw the carbon-strips lengthwise of the platen to bring fresh 15 portions into use.
9. In a front-strike typewriting machine, 20 the combination of a platen, means to support a plurality of carbon-strips in flat condition in front of said platen, means to conduct a plurality of work-sheets in flat condition in front of the platen between the carbon-strips to keep at a minimum any tendency of the work-sheets to drag the carbon-strips with them during line-spacing of the 25 work-sheets, means to draw the carbon-strips lengthwise of the platen to bring fresh portions into use, clamps to secure the carbon-strips in position after they have been so 30 drawn, and means to shift said clamps up and down to present various portions of the 35 fresh sections to the printing line of the platen.
10. In a typewriting machine, the combination with a carriage having a platen in 40 front of which one or more copying strips may be disposed at the printing line, of means comprising a pair of clamps, one at each side of the carriage to support the strips at the printing line, one of said 45 clamps comprising a pair of feed-rolls to feed the strips lengthwise of the platen to bring a fresh portion into use, and means to shift the strips at right angles to the 50 printing line of the platen to bring a fresh portion thereof to said printing line.
11. In a typewriting machine, the combination with a carriage having a platen in front of which one or more copying strips 55 may be disposed at the printing line, of means comprising a pair of clamps, one at each side of the carriage to support the strips at the printing line, one of said clamps comprising a pair of rolls to feed the strips lengthwise of the platen to bring a fresh 60 portion into use, brackets to support said clamps, and means to raise and lower said brackets to shift the strips at right angles to the printing line of the platen to bring a fresh portion of the strips to said printing 65 line.
12. In a typewriting machine, the combination with a carriage having a platen in front of which a plurality of copying strips are disposed and interleaved between plies of a pack of work-sheets, of means comprising two clamps to engage and hold the copying strips, and strip-tensioning means disposed between said clamps to keep the copying strips taut at the printing line. 70
13. In a typewriting machine, the combination with a carriage having a platen in front of which a plurality of copying strips are disposed and interleaved between plies of a pack of work-sheets, of means comprising two clamps to hold the copying strips, 75 a turn-buckle through which the strips are threaded, said turn-buckle being located between said clamps, and a spring to rotate said turn-buckle to keep the copying strips 80 taut at the printing line. 85
14. In a typewriting machine, the combination of a carriage, a platen on said carriage, a supporting device on said carriage inclined upwardly and rearwardly behind said platen, cutters mounted upon said supporting device, said cutters to engage with the folded edges of a fan-fold web while the latter is being fed to the printing point of the platen, to thus slit said web into separate plies as the web is fed to the printing point, 90 and means to facilitate lateral adjustment of said cutters relatively to each other according to the width of the fan-fold web. 95
15. In a typewriting machine, the combination of a platen-carriage, means to conduct carbon-strips in front of the printing line of the platen, a carbon-strip spool mounted on a vertical axis at one side of the carriage from which a fresh supply of the carbon-strips may be drawn to replace used-up portions, the strips extending tangentially from said spool along the front of the platen, means for clamping the ends of the strips, means for tensioning the strips, and means for adjusting the strips and spool bodily up and down to bring unused portions of the strips into use. 100
16. In a typewriting machine, the combination with a carriage having a platen in front of which a plurality of inking strips are disposed and interleaved between plies of a pack of work-sheets, of means including two clamps to hold the inking strips, one of said clamps including means rotatable to feed said strips to bring fresh portions 110 thereof into use. 115
17. In a typewriting machine, the combination with a carriage having a platen in front of which a plurality of inking strips are disposed and interleaved between plies of a pack of work-sheets, of a strip-supply spool, means including two releasable clamps to hold the inking strips after they are unwound from said spool, one of said clamps comprising a pair of rolls rotatable to feed 120 125 130

the strips to bring fresh portions thereof into use.

18. In a typewriting machine, the combination of a flat platen against the front side of which type-bars strike, a feed cylinder behind said platen, a feed-roll engaging the cylinder below and to the rear thereof, an apron under said cylinder to guide a work-sheet, a lip at the lower end 10 of said platen lying close to the platen to form a chute with the apron to keep the work-sheet from being fed up behind said platen, and means at the forward end of said apron to guide the work-sheet up in front 15 of the platen.

19. In a front-strike typewriting machine, the combination with a platen and a carriage therefor, of means for supporting and guiding a set of substantially over-width 20 carbon-paper strips in flat condition on edge in front of the platen, means for holding the ends of every strip, means for advancing interleaved plies of work-sheets in flat condition between the strips, means for longitudinally 25 tensioning the strips, so that partly by reason of their over-width and partly by reason of the tensioning the strips remain in flat condition between the advancing work-plies, and means for adjusting the strips up and down to bring unused 30 portions thereof into use.

20. In a front-strike typewriting machine, the combination with a platen and a carriage therefor, of means for supporting and 35 guiding a set of substantially over-width carbon-paper strips in flat condition on edge in front of the platen, means for holding the ends of every strip, means for advancing interleaved plies of work-sheets in flat 40 condition between the strips, means for longitudinally tensioning the strips, so that partly by reason of their over-width and partly by reason of the tensioning the strips remain in flat condition between the advancing 45 work-plies, said supporting and guiding means including a support upon said carriage for carrying said strips and said strip-tensioning means, and means for adjusting said support bodily up and down.

50 21. In a front-strike typewriting machine, the combination with a platen and a carriage therefor, of means for supporting and guiding a set of substantially over-width carbon-paper strips in flat condition on edge 55 in front of the platen, including a carbon-strip-supply spool erect at one end of the carriage, releasable strip-clamping means at the other end of the carriage, and tensioning means for said strips between the ends

thereof, said spool, said tensioning means 60 and said clamp being adjustable bodily up and down with the strips, to bring unused portions of the latter into use.

22. In a front-strike typewriting machine, the combination with a platen and a carriage therefor, of means for supporting and guiding a set of substantially over-width carbon-paper strips in flat condition on edge 65 in front of the platen, including a carbon-strip-supply spool erect at one end of the carriage, releasable strip-clamping means at the other end of the carriage, and tensioning means for said strips between the ends 70 thereof, and also including a holder for said spool and said clamping means, and means for adjusting said holder bodily up and down on said carriage to bring different unused widthwise portions of the strips into 75 use.

23. In a front-strike typewriting machine, the combination with a platen and a carriage therefor, of means for supporting and guiding a set of substantially over-width carbon-paper strips in flat condition on edge 80 in front of the platen, including a carbon-strip-supply spool erect at one end of the carriage, releasable strip-clamping means at the other end of the carriage, and tensioning means for said strips between the ends 85 thereof, and also including a holder for said spool and said clamping means, and means for adjusting said holder bodily up and down on said carriage to bring different unused widthwise portions of the strips into 90 use, said platen in the form of a plate 95 mounted upon said carriage, and having a forwardly-protruding type-impression ridge, and means below and above the platen to advance the work-sheets in flat condition up between said carbon-strips at all points to 100 which the latter are vertically adjusted.

24. In combination with a typewriting machine having a longitudinally reciprocal carriage and a platen therein, a frame secured to and supported solely by said carriage, a supporting plate upon said frame and inclined upwardly away from said platen, a paper web folded longitudinally back and forth upon itself and movable over said plate, and cutters supported by said frame and engaged with the folded edges of said web while the latter is being moved upon said plate whereby to slit said web into separate strips that are received and fed around said platen. 110 115

This specification is signed this 19th day of July, 1923.

HERVÉ SCHWEDERSKY.
